UNITED STATES PATENT OFFICE.

JAMES P. HOOPER, OF RUXTON, MARYLAND.

FABRIC BAG.

Application filed January 25, 1921. Serial No. 439,744.

To all whom it may concern:

Be it known that I, JAMES P. HOOPER, a citizen of the United States of America, residing in Ruxton, Baltimore County, 5 State of Maryland, have invented certain new and useful Improvements in Fabric Bags, of which the following is a specification.

The invention relates to a bag of textile 10 or woven fabric particularly adapted for use as a mail bag, coal bag or the like. The manufacture of bags for such purposes of textile fabric is understood to have been practiced for many years but such bags have 15 been subject to failure by ripping of the seams and wear, particularly at the bottom. The object of the present invention is to overcome these defects and produce a bag which can be manufactured at a minimum 20 cost as to time and labor.

In the manufacture of the bag which is the subject of the invention in the preferred form the first step is the production of a tube of woven fabric, the sides of which are 25 transversely interwoven at intervals so that the tubular fabric may be cut into bags by severing between the transverse interwoven portions. The present invention further includes so cutting the bag as to provide as 30 a part of each severed section a portion of the tube extending considerably beyond the transverse interwoven portion which part may be turned up against the sides of the bag forming an external reinforce which 35 protects the bottom of the bag from wear and also reduces the stress on the interwoven portion which closes the tube and completes the bottom of the bag.

Preferably the interwoven portion is 40 formed by crossing the warp threads, it being understood that they extend lengthwise of the tube so that when the surplus portion of the fabric beyond the interweave or crossing of the warps is turned up and 45 secured, each warp in fact forms a continuous loop extending from the top of the reinforce downward, around the bottom of the bag and up on the opposite side to the top edge of the bag.

50 In the accompanying drawing I have illustrated a bag constructed in accordance with my invention and also a length of tubular fabric with the warp crossed at intervals ready to be cut into lengths from which 55 bags may be constructed in accordance with my invention.

In the drawing Fig. 1 is a central longitudinal section through a finished bag.

Fig. 2 is an elevation of the bag on a smaller scale.

60 Fig. 3 is an enlarged diagrammatic section showing the arrangement of the threads in the fabric before folding to form the reinforce, the plane of the section being parallel to the plane of the section of Fig. 1. 65

Fig. 4 is a view of a portion of the tube in a fabric ready to be cut into bags, the same being on a reduced scale.

Referring to the drawings by numerals the construction illustrated consists of a bag 1 70 composed of a section of tubular woven fabric 2, the bottom of the bag being formed by interweaving the opposite sides of the tube producing a transverse interwoven portion 3 extending from side to side of the 75 bag and tube. As cut the tubular fabric extends beyond the interwoven portion 3 and is turned upward preferably on the outside of the bag forming a reinforce 4 which may be hemmed at the edges at 5 and seamed 80 to the sides of the bag at 6.

In the form of the invention shown and preferably the warp threads 7 of the fabric forming the tube are crossed at 3 to produce the transversely extending interwoven 85 portion so that each warp thread in the finished bag having the end of the tube turned up to form the reinforce 4, extends down one side of the bag from the mouth or top 8 to the interwoven portion 3 and up the 90 other side of the bag where it is woven into and forms part of the reinforce 4. This produces a bottom structure which is incapable of ripping and is without any weakened portions at all. In fact it is a bag 95

with a double bottom having all the other advantages of a double weight continuous warp fabric, throughout the bottom portion. At the same time it is as easy and cheap to produce as the ordinary bag formed of tubular fabric which can be no stronger than its weakest point, i. e., the bottom seam. The process of weaving the transverse interwoven portion is quicker and easier to produce as well as stronger than ordinary sewing. Practically the only additional expense of construction being that incident to the actual cost of the extra length of fabric forming the reinforce 4. The manner of applying this reinforce to the structure as hereinbefore described is cheaper than any other known method of reinforcing including the 100 105 110

obvious method of sewing an extra thickness of fabric to the inside or outside of the bag.

Having reference to Fig. 4 of the drawing I have illustrated a tubular fabric 9 interwoven at intervals at 3 adapted to be cut transversely at convenient points as indicated by reference character 11 to produce tubular sections from which the bags may be conveniently constructed in accordance 10 with my invention. Each section as shown includes a reinforcing portion 4.

I have thus described specifically and in detail a bag embodying my invention in the preferred form, however, the specific terms 15 herein are used descriptively rather than in a limiting sense, the scope of the invention being defined in the claim.

What I desire to secure by Letters Patent is:—

A bag composed of tubular textile fabric 20 having the opposite sides interwoven by crossing the warp, the tubular fabric beyond the interwoven portion being turned up against the sides of the bag and secured at the edges whereby the respective warp 25 threads are caused to extend down one side of the bag, around the bottom and up on the opposite side.

Signed by me at Baltimore, Maryland, this 20th day of January, 1921.

JAMES P. HOOPER.
